CLAIM

The ornamental design for a lacrosse head, as shown and described.

DESCRIPTION

FIG. 1 is a bottom, rear, right side perspective view of a lacrosse head showing our new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof;
FIG. 8 is a top, front, left side perspective view thereof;
FIG. 9 is a bottom, rear, left side perspective view thereof; and,
FIG. 10 is a top, front, right side perspective view thereof. The dash-dash broken lines represent portions of the lacrosse head that form no part of the claimed design.

1 Claim, 10 Drawing Sheets
